J. NEEDHAM.

HIGH PRESSURE GOVERNOR VALVE.
APPLICATION FILED AUG. 13, 1919.

1,373,906.

Patented Apr. 5, 1921.

Inventor
Joseph Needham,
By his Attorneys

UNITED STATES PATENT OFFICE.

JOSEPH NEEDHAM, OF NEW YORK, N. Y.

HIGH-PRESSURE GOVERNOR-VALVE.

1,373,906.

Specification of Letters Patent. Patented Apr. 5, 1921.

Application filed August 13, 1919. Serial No. 317,252.

To all whom it may concern:

Be it known that I, JOSEPH NEEDHAM, a citizen of the United States, and residing at New York, in the county of New York and State of New York, have invented certain new and useful Improvements in High-Pressure Governor-Valves, of which the following is a specification, such as will enable those skilled in the art to which it applies to make and use the same.

This invention relates to high pressure governor valves and particularly to devices of this class designed for use in connection with my improved method of and apparatus for compressing a delivery fuel gas, shown and described in an application for Letters Patent of the United States filed by me of equal date herewith; and the object of this invention is to provide a pressure governor and control valve of the class and for the purpose specified which is simple in construction, efficient in use and which will control the supply of fuel gas through the delivery of service lines at a positive and set pressure independent of the pressure in the gas supply service lines and independent of the pressure and volume in use in the plant, and independent of the number of the burners or gas using appliances to which the gas is supplied, the pressure at each burner or gas using appliances remaining the same at all times; a further object being to provide a pressure controlling valve of the class specified which does not employ diaphragms, springs or other complicated mechanism which are a frequent source of trouble in valves of this class, and which is especially designed to prevent "chatter" in the operation thereof and is quick to respond and smooth and even in action, and susceptible to the slightest variation, and cannot be put out of adjustment; and with these and other objects in view the invention consists in a valve of the class and for the purpose specified, constructed as hereinafter described and claimed.

The invention is fully disclosed in the following specification, of which the accompanying drawing forms a part, in which the separate parts of my improvement are designated by suitable reference characters in each of the views, and in which: —

Figure 1 is a side view of my improved pressure governor and controlling valve;

Fig. 2 is a section on the line 2—2 of Fig. 1; and,

Fig. 3 a sectional detail of the construction shown in Fig. 2 and on an enlarged scale.

In carrying my invention into effect, I provide a valve casing 5 of the usual general form and provided at one side with an inlet opening 6 and at the opposite side with a discharge opening 7, and the casing 5 is provided with an interior horizontal partition member 8 which divides casing into an inlet chamber 9 and an outlet or discharge chamber 10.

The valve casing 6 is provided at the top thereof with an interiorly threaded neck 11, and I also provide a casing 12 having a threaded neck 13, which is screwed into the neck 11 of the valve casing 5 and which is provided with a detachable cover 14 having a centrally threaded neck 15 closed by a detachably threaded cap 16.

I also employ a tubular piston rod 17, one end of which is threaded and passes through the neck 15 and is provided within the cap 16 with a set nut 18 and the end of which, within said cap 16, is closed by a threaded plug 19. I also provide a plunger valve 20 which operates to open and close a port or passage 21 in the partition 8 of the valve casing 5, and said valve is provided with a cylindrical body 22 which passes loosely or movably through the neck 13 of the casing 12, and within the cylindrical body 22 of the valve 20 is a piston chamber 23, the top of which is closed by a threaded plug 24 and the piston rod 17 passes loosely or movably through the threaded plug 24 and through the chamber 22, and the lower end thereof which is closed by a threaded plug 25 fits in and is vertically movable in a socket 26 at the bottom of the piston chamber 23.

I also provide a plurality of weights 27, 28, 29 and 30, as shown in the drawing, which are placed in a chamber 31 in the casing 12, and through which the piston rod 17 passes and the weight or weights 27—30 rest on the top of the plunger body 22 of the valve 20, as clearly shown in Fig. 2, and control the movement of the valve 20, as will be readily understood.

The piston rod 17 is provided within the chamber 23 with a piston 32 having a port or passage 33, and the rod 17 is provided

below said piston with a corresponding port or passage 34, and in the use of this device oil or lubricating material is passed through the hollow piston rod 17 and through the 5 port or passage 34 therein into the chamber 23 and is free to pass through the port or passage 33 in the piston 32, and this forms a dash-pot which permits, or insures, the free and easy movement of the plunger valve 10 on the rod 17 and prevents what is known as "chatter" in the operation of valves of this class and also insures responsive action under all conditions of pressure, or changes therein, and a smooth, even and positive 15 action of the device as a whole.

In the use of this device the inlet port 6 of the valve casing is in communication with the delivery or supply pipe or line of the apparatus, which delivers the fuel gas to the 20 burners or appliances for using the same, and this gas enters the chamber 9 in the bottom of the valve casing at the pressure required for the burners or other gas consuming appliances, and if this pressure rises 25 above the degree required, the valve 20 will be raised and the over-pressure will be discharged from the discharge side of the valve casing, as will be readily understood, and as shown and described in the application herein 30 before referred to, and by a proper use of the weights 27 to 30, the pressure necessary to operate the valve 20, as above described, may be determined and regulated at all times and under all conditions.

In the accompanying drawing and foregoing description I have shown and described the details of construction which I prefer in carrying my improvement into effect, but it will be understood that the invention described and claimed herein is not limited to such details of construction, and changes therein and modifications thereof may be made, within the scope of the appended claims, without departing from the 45 spirit of my invention or sacrificing its advantages; and while I have shown and described my improvement as particularly designed for use in connection with an apparatus for supplying high pressure fuel gas 50 to burners or burner appliances, it will be understood that my invention is not limited to this use and the governor valve shown and described herein may be used for various other purposes and in connection with 55 various other forms of apparatus in which it is desired to control the pressure of liquid or gaseous substances.

Having fully described my invention, what I claim as new and desire to secure by 60 Letters Patent, is:—

1. A valve device of the class described comprising a main valve casing, a supplemental cup-shaped casing mounted in connection with said main casing and provided 65 with a detachable cover, a valve seat in the

main casing, a valve movable toward and from said seat and adapted to form a gas-tight connection when seated, said valve being provided with a plunger body which projects into the supplemental casing, a dashpot within said plunger body and formed by a tubular rod detachably mounted in the detachable cover of the supplemental casing and passing into said plunger body and provided therein with a piston, 75 and a plurality of weights mounted in the supplemental casing and coöperating with said valve or the plunger body thereof to hold the valve in its seated position under predetermined pressure.

2. A valve device of the class described comprising a main valve casing, a supplemental casing mounted in connection with the main casing, a valve seat in said main casing, a valve movable toward and from 80 said seat and adapted to form a gas-tight connection when seated, said valve being provided with a plunger body which projects into the supplemental casing.

3. A valve device of the class described comprising a main valve casing, a supplemental casing mounted in connection with the main casing, a valve seat in said main casing, a valve movable toward and from 85 said seat and adapted to form a gas-tight connection when seated, said valve being provided with a plunger body which projects into the supplemental casing, a dashpot within said plunger body and formed by a tubular rod detachably mounted in 90 connection with the supplemental casing and passing into said plunger body and provided therein with a piston, and a plurality of weights mounted in the supplemental casing and coöperating with said valve or the 95 plunger body thereof to hold the valve in its seated position under predetermined pressure.

4. A valve device of the class described comprising a main valve casing having a 100 port or passage, a supplemental casing mounted in connection with the main casing, a valve for controlling said port or passage and provided with a plunger body which projects into the supplemental casing 105 and in which is a piston chamber, a stationary tubular piston rod mounted in connection with said supplemental casing and passing into said plunger body through said chamber, a ported piston mounted on said 110 rod within said chamber, said rod being provided within said chamber and below said piston with a port, and means whereby a liquid may be passed into said chamber through said tubular piston rod and said 115 port to form a dashpot within said plunger body.

5. A valve device of the class described comprising a valve casing having a passage, a valve for controlling said passage and hav- 120

ing an integral plunger body in which is a piston chamber, a stationary piston rod passed into said plunger body and through said chamber, a piston mounted on said rod within said chamber, and means coöperating with the plunger body of said valve for normally holding the same in a closed position under predetermined pressure.

In testimony that I claim the foregoing as my invention I have signed my name in presence of the subscribing witnesses this 11th day of August, 1919.

JOSEPH NEEDHAM.
